Primary Examiner — Martie K Holtje

(74) *Attorney, Agent, or Firm* — Venable LLP; Michele V. Frank, Esq.

(57) **CLAIM**

The ornamental design for an animal leash, as shown and described.

DESCRIPTION

FIG. 1 is a perspective view of an animal leash showing a first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment of my design of FIG. 1;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.

The structural features depicted by broken lines have been shown for the purpose of illustrating portions of the animal leash that form no part of the claimed design.

1 Claim, 10 Drawing Sheets
